PHONOGRAPHIC RECORD CASE OR THE LIKE

Arthur F. Johnson, Northbrook, Ill., assignor to Anderson Tool & Mfg. Co., Chicago, Ill., a corporation of Illinois

Filed May 22, 1959, Ser. No. 56,025

Term of patent 14 years

(Cl. D87—5)

FIG. 1

FIG. 3

Fig. 1 is an endwise perspective view of a phonographic record case or the like showing my new design;

Fig. 2 is a front perspective view of the same;

Fig. 3 is an endwise perspective view of the same in open condition.

I claim:

The ornamental design for a phonographic record case or the like, as shown.
